UNITED STATES PATENT OFFICE.

MELLEN BRAY, OF NEWTON, MASSACHUSETTS.

DESIGN FOR A LACING-HOOK FOR BOOTS, SHOES, &c.

SPECIFICATION forming part of Design No. 12,242, dated May 3, 1881.

Application filed March 23, 1881. Term of patent 14 years.

To all whom it may concern:

Be it known that I, MELLEN BRAY, of Newton, in the county of Middlesex and State of Massachusetts, have invented a new and original Design for Lacing-Hooks for Boots and Shoes and other purposes, of which the following, taken in connection with the accompanying drawings, is a specification.

My invention relates to the general form or contour of lacing-hooks to be secured to boots, shoes, gloves, or other articles to receive the lacing-cord, and is clearly illustrated in the accompanying drawings, in which—

Figure 1 is a perspective view of my improved hook. Fig. 2 is a plan of the same, and Fig. 3 is a central vertical section.

The leading feature of my design is a hook having an outer head or disk, the outer face of which has formed therein a recess surrounded by a circular bead, and connected by a concavo-convex neck to an inner disk or flange, which rests upon the material when applied thereto for use; also, a hook having a head or disk, in the outer face of which is stamped or otherwise formed a circular sunken recess, said disk being connected by a concavo-convex neck at one side to a second disk or flange, which rests upon the material when applied thereto for use, and also provided with a cy-

lindrical tubular shank for securing it to the material.

In the drawings, *a* is the outer disk or head, having in its outer surface the recess *a'*, inclosed by the bead *a²*, and connected by the concavo-convex neck *b* to the flange *c* upon the upper end of the cylindrical tubular or hollow shank *d*, as shown. The neck *b* connects the head *a* with the flange *c* at one side, and has its convex side inward, as shown.

I claim—

1. The design for a lacing-hook herein shown and described, the same consisting of the head *a*, having the recess *a'* and inclosing-bead *a²*, the circular flange *c*, and the concavo-convex neck *b*, connecting said head and flange at one side.
2. The design for a lacing-hook herein shown and described, the same consisting of the head *a*, provided with the recess *a'* and the bead *a²*, the hollow or tubular cylindrical shank *d*, the disk or flange *c*, and the concavo-convex neck *b*, connecting the head *a* and the flange *c* at one side.

Executed at Boston, Massachusetts, this 21st day of March, 1881.

Witnesses: MELLEN BRAY.
E. A. HEMMENWAY,
WALTER E. LOMBARD.
